DANIEL JOHNSTON, OF CRANBERRY, OHIO.

Letters Patent No. 97,926, dated December 14, 1869.

IMPROVEMENT IN FENCE.

The Schedule referred to in these Letters Patent and making part of the same.

To all whom it may concern:

Be it known that I, DANIEL JOHNSTON, of Cranberry, in the county of Crawford, and in the State of Ohio, have invented certain new and useful Improvements in Fences; and do hereby declare that the following is a full, clear, and exact description thereof, reference being had to the accompanying drawings, and to the letters of reference marked thereon, making a part of this specification.

The nature of my invention consists in the peculiar construction of the posts in which fence panels are secured.

In order to enable others skilled in the art to which my invention appertains, to make and use the same, I will now proceed to describe its construction and operation, referring to the annexed drawings, in which—

A A represent two sills, placed a suitable distance apart, and connected by cross-pieces B B, on top.

Between the sills are placed the two upright posts

C C, their outer sides being notched or cut out, as seen in fig. 1, so as to partially rest on two of the cross-pieces B B.

The upright posts C C are braced by the inclined bars D D, the lower ends of which are cut so as to rest on both the sills A A, and the centre extends down between the same.

The upper ends of the braces D D are cut out, so that they extend one on each side, and brace both the upright posts C C, as seen in fig. 1.

Having thus fully described my invention,

What I claim as new, and desire to secure by Letters Patent, is—

The combination and arrangement of the sills A A, cross-pieces B B, uprights C C, and braces D D, all as shown and described.

In testimony that I claim the foregoing, I have hereunto set my hand, this 19th day of July, 1869.

DANIEL JOHNSTON.
